ELECTRODE FOR GLOW-DISCHARGE DEVICE

Bernard Schwartz, Watertown, Mass., assignor to Sylvania Electric Products Inc., a corporation of Massachusetts

Application March 16, 1954, Serial No. 416,499

1 Claim. (Cl. 315—353)

The present invention relates to gaseous discharge devices. In particular, the invention is concerned with gaseous discharge tubes for controlling guided transmission of radiant energy, and specifically to keep-alive electrodes and methods of making keep-alive electrodes for such tubes.

In microwave transmission-control tubes where the invention finds particular value, it is customary to employ a keep-alive electrode in assembled relation with gap-forming electrodes for maintaining a limited volume of gas in the gap region in weakly ionized condition. In transmit-receive tubes, for example, this ionization renders the tube instantaneously responsive to high levels of input radiant energy to break down in an arc discharge. In such tubes, the keep-alive electrode must be of a construction such that it will not cause deterioration of the gaseous fill of the tube and will be capable of withstanding the usual severe operating conditions. A serious drawback for long tube life is sputtering of the keep-alive material which tends to change the tube characteristics, and the growth of "whiskers" at the keep-alive, tending to short-circuit the tube at that part.

It is an object of the present invention to provide an improved glow-discharge electrode which may be incorporated in gaseous discharge devices, prominently as a keep-alive in gaseous transmission control tubes.

It is a further object of the present invention to provide a gaseous transmission control tube embodying a keep-alive electrode exhibiting properties promoting long tube life.

A still further object of the invention is the provision of an integral keep-alive electrode of a form readily made and incorporated into gaseous discharge devices.

Partially reduced or semiconducting titania has been found to exhibit desirable keep-alive characteristics, prominently promoting long transmit-received tube life. However, there are practical difficulties involved in incorporating bodies of material in keep-alive electrodes. There exists a need for a keep-alive exhibiting optimum properties for successful operation of such tubes with physical characteristics promoting manufacture by simplified and direct techniques.

In an illustrative embodiment, demonstrating features of the present invention, a keep-alive electrode of zirconium metal is incorporated in a gaseous transmission-control tube. The keep-alive electrode of zirconium is beaded with a vitreous insulating sheath, and is treated in a restricted region to obtain desired keep-alive properties. This keep-alive subassembly is incorporated into the control tube by suitable techniques, as described in copending application Serial No. 237,258, filed by Paul Gates, now Patent No. 2,740,186, issued April 3, 1956.

In accordance with further aspects of the invention, the keep-alive electrode has an active region provided with a layer or surface of the semiconductive, refractory oxide of the keep-alive metal. Advantageously, this active layer or region is formed in situ by oxidation. One method found suitable for processing the keep-alive in-

2

volves beading or sheathing the keep-alive metal to provide a well-defined surface serving as the active keep-alive region, and providing this surface with an oxygen-deficient oxide layer by electrolytic or anodic oxidation.

5 A further effective method for situ treatment includes the steps of developing the oxide at the active region by heating in air or other oxidizing atmosphere, followed by heating in a controlled reducing atmosphere such as hydrogen to render the oxide oxygen-deficient.

10 The zirconium thus described combines both properties of being readily sealed to glass, having an appropriate thermal coefficient of expansion, and being adaptable to formation of a bonded refractory semi-conductive oxide. Other metals of the zirconium group as titanium and hafnium may be used in broadly applying an aspect of this invention or by joining such metal to a glass-sealing lead and forming an oxide in situ on such metal.

The above and still further objects, features, and advantages of the invention will be best appreciated by 20 reference to the following detailed description when taken in conjunction with the drawings, wherein:

Fig. 1 is an enlarged elevation, with parts sectioned for clarity, of a portion of an illustrative keep-alive assembly;

25 Fig. 2 is a greatly enlarged detail of the keep-alive of Fig. 1; and

Fig. 3 is an elevation with parts sectioned, of an illustrative gaseous transmission control tube embodying features of the present invention.

30 Reference will now be made to the subassembly and processing of a keep-alive electrode, illustrative of the present invention, preliminary to final mounting and orienting in relation to the gap-forming electrodes of the well-known gaseous transmission control tubes. As seen in Fig. 1, the keep-alive electrode 10 includes a conductive zirconium body 12 and is provided with an insulating sheath or bead 14 as of glass covering the body 12 except for a limited, well-defined region 12a. With zirconium as the keep-alive material, advantages are realized in respect to simplicity since the zirconium may directly serve as a terminal and may have a directly bonded glass sheath 14.

The electrode body 12, is initially enclosed in the insulating sheath 14 except for the active face region 12a, which is to be exposed in the breakdown or discharge gap of the tube, by inserting the electrode body 12 in a glass tube and subjecting the assembly to appropriate sealing temperatures to bond the sheath to the zirconium body. For example, a hard glass tube of the Kovar-sealing glasses, such as Corning #7052, is suitable for sealing to the zirconium. A heavy glass button 16 is added for ultimate sealing in place, as will be clear later.

In an advantageous illustrative process the sheathed keep-alive zirconium electrode 10 has its active exposed face 12a rendered semiconductive and refractory in situ.

55 One method of treatment involves anodic or electrolytic oxidation by immersing the active face region 12a of the keep-alive electrode 10 in a suitable electrolyte, such as nitric acid, and applying a positive potential to the keep-alive electrode serving as an anode. This may be accomplished by directly connecting the positive potential with an appropriate cathode, as a platinum cup receiving the electrolyte. Details of an anodic oxidation treatment may be found in an article in the Journal of the Electro-Chemical Society, vol. 100, #12, pages 531-537 of 1953. The anodic oxidation treatment transforms the exposed region of the zirconium electrode into an adherent, semiconductive and refractory zirconium oxygen-deficient oxide layer having highly desirable keep-alive properties.

70 A further method of treatment in situ of the keep-alive electrode to impart desired semiconductive properties to

its exposed region is by heating the exposed area in air to form zirconium dioxide. Thereafter, the metallic oxide area is reheated in a reducing atmosphere, such as hydrogen, and at temperatures ranging from approximately 500° C. to 1100° C., and for an appropriate period gauged to accomplish only partial reduction so as to yield a semiconductive adherent oxide.

The keep-alive electrode 10 as shown in Figs. 1 and 2 is sealed to a metal-to-glass sealing supporting sleeve 18, by arranging the keep-alive electrode 10 concentrically of the sleeve 18 and axially displacing the electrode while developing localized heat at the end of the sleeve 18 remote from the head or flange end 20.

This intermediate assembly is then joined to a conical gap-forming electrode 22, as shown in Fig. 3, by brazing the lateral flange 24 of the electrode to the flanged end or head 20 of the sleeve 18, care being exercised to obtain proper centering and spacing of the exposed and treated face 12a of the keep-alive relative to the tip of the gap-forming electrode 22. Conventionally, the active face 12a of the keep-alive electrode is spaced a few thousandths of an inch from the opening in the tip of the discharge or gap electrode 22, both radially and endwise. Assembly of the gap-forming electrode 22, with a further conical gap-forming electrode 26, as in the illustrative transmit-receive tube of Fig. 3, will best be appreciated by reference to the mentioned applications. The foregoing assembly method is more fully detailed in the above mentioned application Serial No. 237,258, now Patent No. 2,740,186.

Briefly, the gap-forming electrodes 22, 26, are arranged across a length of wave guide 30 having flanges 32, 32' for connection to a microwave system. The ends of the wave guide 30 have resonant windows 34, 34'. Electrode 26 may be of deformable construction for critical adjustment by engagement from the exterior of the waveguide 30, as by provision of a complementary body (not shown) within the electrode 26. With multiple electrode pairs, the gaps are normally spaced along the waveguide a distance equal to an effective quarter wavelength at the center frequency of the transmit-receive device.

The waveguide 30 is conventionally filled with an electron capture gas, preferably a noble gas such as argon, mixed with a quenching gas, such as water at a total pressure of the order of twenty-five millimeters of mercury. 45

In operating the illustrative transmit-receive tube of

Fig. 3, a current is passed between the keep-alive electrode 10 and the discharge electrode 22; normally several hundred volts is applied between the keep-alive electrode 10, directly serving as a terminal, and the gap-electrodes 22, 26, establishing a glow discharge. The keep-alive potential maintains a limited volume of gas ionized in a confined region adjacent the gap. Upon incidence of high level signal bursts, the limited volume of weakly ionized gas promotes an abrupt formation of an intensely ionized discharge thereby switching the waveguide transmission path from one in which low level signals are transmitted, to one in which high level signals are almost entirely reflected. The use of such devices is well known, and requires no further elaboration.

From the foregoing, it can be appreciated that keep-alive electrodes embodying features of the present invention exhibit desirable keep-alive properties and are mechanically suited to be incorporated in a variety of tube constructions without extreme fabrication difficulties, especially in view of the physical geometry of environment electrode constructions, and the frequently critical spacing requirements.

From the foregoing disclosure of the several aspects of the present invention, those skilled in the art will find varied applications of the invention as well as various further modifications. Accordingly, the appended claim should be interpreted broadly, consistent with the spirit and scope of the invention.

What is claimed is:

30 A "keep-alive" electrode for a glow-discharge device comprising an elongated zirconium rod having a terminal end and a discharge end, a layer of semi-conductive zirconium oxide adhering to the lateral end surface of the discharge end of said rod, and a glass sheath bonded to and completely covering the discharge end of said rod except for said lateral end surface.
